9614X Hugh Barclay
Gallows Patent

The Schedule referred to in these Gallows Patent and making part of
the same containing a description in the words of the said Hugh
Barclay himself of his improvement in the Threshing Machine.

To all to whom these presents shall come. Be it known that Hugh Barclay of the town of Lapeer, in the County of Rockbridge and State of Virginia have invented a new and useful improvement in the Threshing Machine now known and distinguished from all other Threshing Machines as "Barclay's rotary, supple or flat Threshing Machine" adapted to all the purposes of threshing as well grain of all kinds as also Rice, Potatoes, corn and other grains. This improvement consists in operating with a metallic supple or flat revolving upon a rod of wrought iron, steel, copper or other metal of sufficient strength to effect the purposes intended. The manner of constraining the flat or supple may be varied according to the fancy of the person intending to build or use the machine, that is whether the hole through the flat shall be drilled or punched or whether it shall be simply drawn and lashed or welded. The mode recommended is to have wrought iron drawn into bars of suitable size to make the flats one and one eighth of an inch thick, let the flat be cut of any length that may please, having carefull to have them all of the same length, this may be from three to six inches long, as may be required by the velocity of the machine. The supple or flat is made by inserting a hole near to one end of sufficient size to receive the rod B. on which the flat has a rotary action when the machine is in motion. The washer C. may be made of cast or wrought iron, leather or other substance of suitable strength and thickness, the washer is placed alternately between the flats or supples so that their action shall not interfere with each other, a washer of three eighths of an inch in thickness would be calculated for the threshing of wheat, Rye and Oats. The horizontal rod D. on which the flats and washers are fixed should be round and of sufficient strength

to resist the action of the machine. It may be fastened by screws or riveted a bayonet to heads or arms or fastened to a cylinder by any mode that fancy or convenience may dictate save this, has that the fastenings be of sufficient strength and number to prevent them from breaking out or the rod breaking off by the action of the machine. The length of the horizontal rods and their number as well as the number of flints and their length may be regulated by a knowledge of the strength of the propelling power, always observing that a slow motion requires a longer flint or bullet than a motion of greater velocity. The advantages of this improvement are that it throws as a stone as any other machine, requires less motive power to operate with effect than another and is not injured by hard substances passing through the machine when in operation by the fact that the bullet or flint is instantly thrown back within the weight of which it overcomes any substance that does not yield to its force and immediately resumes its position for work by the centrifugal force of the revolving cylinder heads or arms to which the flints may be fixed. What I claim as my invention and not previously known or described in the foregoing is the starting flint, or flint revolving upon a rod as before described.
